[57] **CLAIM**

The ornamental design for a swim fin, as shown and described.

DESCRIPTION

FIG. 1 is a perspective view of a swim fin showing my new design;

FIG. 2 is a bottom plan view thereof;

FIG. 3 is a rear elevational view thereof;

FIG. 4 is a front elevational view thereof;

FIG. 5 is a top plan view thereof; and,
FIG. 6 is a side elevational view thereof, the opposite side elevational view being a mirror image of that shown.
